vided for heating the combustion chambers, such for example as have heretofore been employed in similar kilns.

Referring to Fig. 1, slabs or abutments 52 of refractory material are inserted in the arch 26 and project downwardly beyond the lower surface of this arch. The muffles 51 rest against the slabs 52 and are sealed to the slabs by any suitable means such as a refractory cement. The lower ends of the muffles 51 preferably rest in depressions or grooves 53 in the benches 25 and may be sealed thereto by means of a similar refractory cement.

The muffles illustrated in Figs. 1 to 3 are formed in sections or units, each of which is provided with a corrugated back wall 55 facing the combustion chamber 35 and a corrugated front wall 56 facing the treating chamber 36, which walls are joined or connected by means of spaced webs, the latter being preferably formed integral with the front and back walls. For example, upright end walls or webs 57 and 58 connect the ends of the front and back walls, and these webs are preferably provided with interlocking parts adapted to connect with adjacent muffle sections. For this purpose, the end wall 57 may have a projecting tongue 59 and the other end wall 58 may have a complementary recess or groove 60. When the muffle sections are installed in a furnace or kiln, the tongue of one muffle interfits with the groove in an adjacent muffle, as indicated in Fig. 3. The front and back walls of the muffle may also be joined intermediate of their ends by additional vertical connecting webs 61, thus producing a strong and highly effective structure. By having the corrugations of the front and back walls arranged as shown in Figs. 1 to 3, the webs extend from an inwardly extending trough of one wall to a crest of another wall.

It will be noted too that in the construction shown in Figs. 1 to 3, the front wall 56 of each section is not coextensive with the back wall, but terminates at its upper and lower ends respectively below and above the corresponding ends of the back wall. This provides for the admission of air or kiln atmosphere into the lower end of the space between the two walls of the muffle, for the upward passage of the air in the space between the two walls, and for the discharge of this air at the upper end of this space.

Muffles constructed as described are very effective in the heating of the material under treatment for several reasons. The amount of radiation of heat depends upon the surface area from which the heat is radiated, and since a corrugated surface has much larger area than a flat surface, a correspondingly increased radiation of heat results. Radiation of heat is generally in a direction perpendicular to the surface from which it is radiated. By using a corrugated surface, the heat is radiated from this surface in a number of different directions, so that it is not concentrated upon the material under treatment to the extent that would happen if a flat radiating surface were used. Furthermore, with the muffle described, convection currents of gas or air are produced within the treating chamber, which have the advantage of distributing the heat through the material under treatment rather than concentrating it upon the outer surface thereof. By providing a muffle in which the cooler air can enter between the two walls of the muffle at the lower end thereof, become heated during its passage between the walls, and then

discharged at the upper ends thereof, strong convection currents are produced. This form of muffle is, consequently, particularly desirable for use in treating certain types of material such, for example, as china or porcelain ware in which the separate pieces are spaced from each other so that convection currents can flow readily through the spaces between the individual pieces of the ware.

The corrugations of the muffle also materially strengthen the same. A corrugated muffle wall is far less likely to buckle than a straight walled muffle and a double walled corrugated muffle has a still greater resistance to buckling or other deformation. A muffle of this kind has been found to be capable of withstanding higher temperatures for longer periods of time than a single wall muffle. The upright webs also greatly strengthen the muffle in that they enable each wall of the muffle to reinforce the other wall.

In order to make a tight seal between the corrugated back wall 55 of the muffle and the downwardly extending abutment or slabs 52 of the furnace or kiln, the upper edge of the rear face of the back wall of the muffle is provided with a rib or reinforcing bead 64 which extends into the troughs of the corrugations of the back wall and the rear face of which forms a flat surface extending parallel to the front face of the slab 52 with which the muffle cooperates. This rib or reinforcement 64 may be cemented to the slab 52 to form a substantially air-tight joint. The reinforcing part 64 also increases materially the strength of the muffle and reduces the danger of breaking of the upper end of the same.

In the particular construction shown in Figs. 1 to 3, the combustion chambers are sealed in such a manner that no products of combustion enter into the treating chamber, so that all heat passing into the treating chamber from the combustion chambers must pass through the muffles. In the modified construction shown in Figs. 4 and 8, the muffles are substantially identical in construction with the muffles shown in Figs. 1 to 3, except that the back wall of the muffle is provided with holes 66, these holes being preferably formed in the back wall below the lower edge of the front wall of the muffle. These holes may be of a desired size and number to admit the required amount of combustion gases into the treating chamber 36. It is desirable in some cases to have an oxidizing atmosphere in the treating chamber and in other cases, a neutral atmosphere is desired, while in still other cases, it may be desirable to have a reducing atmosphere in the treating chamber. These varied conditions depend, of course, upon the material which is being acted upon in the treating chamber and upon the results desired. By means of the construction shown in Figs. 4 and 8, a neutral or reducing atmosphere may be provided in the treating chamber 36 by controlling combustion in the combustion chambers.

In cases where it is desired to convey a lesser amount of heat to the treating chamber 36 from the combustion chamber or chambers, and where long life of the muffle is of primary importance, the construction shown in Figs. 5 and 9 may be provided in which the front wall 56b of the muffle is of the same or substantially the same length as the back wall 55. The front wall 56b of the muffle, consequently, extends to the bench 25 and prevents the entrance of air or gas into the lower end of the space between these two walls so that no convection currents through the

muffle itself are produced. In this construction, however, the radiation of heat is directed in a large number of different directions because of the use of the corrugated front wall 56b so that the radiation of heat is distributed over a large area. This construction, consequently, eliminates excessive concentration of radiation on that portion of the ware or material which is nearest to or faces the muffle.

A further modification is shown in Figs. 6, 10 and 11, in which the muffles have a flat back wall 67 and in which the front wall 68 is corrugated. This muffle incorporates many of the advantages of muffles having both front and back walls corrugated and yet is somewhat less expensive to manufacture, since the cost of manufacturing a flat wall is less than that of a similar corrugated wall. This muffle is also shown with a forwardly extending reinforcing rib or projection 69 which reinforces the upper edge of the muffle. It will be noted also that in this construction, the front wall terminates at a distance below the upper end of the muffle, thus permitting direct radiation from the flat back wall into the treating chamber above the portion thereof in which the material under treatment is located. In this manner, a large amount of heat is radiated above the upper end of the front wall 68 of the muffle against the arch 26, by which it is reflected downwardly upon the material under treatment.

Fig. 7 illustrates another embodiment of this invention which includes a four-piece muffle constructed so that the combustion chamber is formed within a space confined by the four pieces of the muffle. In this construction, a muffle 51b is employed, facing the treating chamber and this muffle may be identical in construction with the one shown in Figs. 5 and 9, except that the muffle 51b is of less height than the one shown in Figs. 5 and 9. The passages between the inner and outer walls of this muffle communicate with a hole 70 in the top wall 71 of a bottom muffle member 72, the bottom wall 73 of which may rest upon the bench 25. This bottom muffle member 72 may be of plain flat walled construction, but may be reinforced by means of a plurality of transverse webs 74 corresponding to the webs 61 and the end walls shown in Fig. 3, thus leaving passages which communicate at their opposite ends with similar passages in the front muffle member 51b and a back muffle member 76. The bottom muffle member 72 may be attached to the back muffle member 76 which in turn is attached to a top muffle member 77. All of these muffle members are of the double-walled construction, and are so formed as to be fitted together as clearly shown in Fig. 7 to form continuous passages 78 having an opening 79 adjacent to the platform member 38 of the car and another opening 89 near the arch 26. This causes convection currents to be set up in the treating chamber 36 through the bottom, back and top sections of the muffle as well as through the front section. The front section also directly transmits heat to the treating chamber by radiation through the corrugated walls thereof. The spaces between the walls of the front muffle member 51b preferably terminate in holes or openings in the bottoms and top muffle members to enable this member to transmit heat both by convection and radiation.

In Figs. 12 to 14, still another modified form of muffle is illustrated. This muffle is similar to the one shown in Figs. 1 to 3 except that the corrugations are differently formed and the connec-

tions of the upright webs with the corrugated walls are differently made. In this construction, the back wall 83 is connected with the front wall 84 by means of a series of webs 85. The front wall 84 terminates at a distance from the upper and lower ends of the back wall and the webs 85 extend to the bottom of the back wall but terminate at the upper end of the front wall. From about the level of the top of the front wall to the top of the back wall short ribs or webs 86 extend forwardly from the troughs of the corrugations approximately to the plane of the crests thereof as plainly shown in Fig. 14. The tongues and grooves 87 and 88 in the opposite webs or end walls are formed in the portions of these end walls below the upper edge of the front wall and are only partially formed in the upper ends 86 of these webs. By means of this construction, muffles of great rigidity and strength are produced without waste of material. By forming the webs on the portions of the corrugations of the back wall which extend farthest into the combustion chamber, a more uniform heating of the corrugated back wall is produced, since the most rearwardly extending portions of the corrugations are, of course, heated to the greatest extent by the combustion gases in the combustion chamber. By forming the webs 85 and 86 integral with these portions of the corrugations, heat is conducted forwardly by the webs 85 to the front wall of the muffle, which tends to reduce the temperature of the rearwardly extending portions of the corrugations of the back wall. Consequently, the temperature of the back wall is rendered more uniform throughout and is, consequently, less liable to damage. This type of muffle is, consequently, desirable under some conditions of use.

Figs. 15 and 16 show a slight modification of the invention in which the end walls and connecting webs, which are formed integral with the front and back walls, have a joint which extends completely from one end to the other of these end walls and webs.

The muffles herein described are thoroughly practical and are of greater rigidity and strength than muffles heretofore produced. The modulus of rupture of the walls of the muffle is improved by making the same in corrugated form and the corrugated walls provide from 25% to 40% greater radiation area than corresponding flat walled muffles would have. By means of the double walled muffle, a greater proportion of the heat is conducted to the material under treatment by means of convection currents, and a lesser amount by radiation, and the heat which is transferred by radiation is distributed or broken up in such a manner as not to be excessively concentrated upon the portion of material or ware which is nearest to the muffles.

The word "kiln" is herein employed to designate any type of furnace or heating device in which muffles may be used.

I claim as my invention:

1. A muffle adapted to be incorporated substantially vertically with the walls of a kiln and co-operate therewith to form a combustion chamber, said muffle comprising spaced inner and outer walls corrugated on vertical lines, said corrugations being related so as to dispose all portions of said walls in parallel relation, end walls integral with said inner and outer walls, and transverse webs formed integrally with and connecting said inner and outer walls and uniformly spaced from said end walls and each other,

said end walls and webs extending from the bottom to the top of said outer wall.

2. A muffle adapted to be incorporated with the walls of a kiln and co-operate therewith to form a combustion chamber, said muffle comprising an outer wall corrugated on vertical lines from side edge to side edge thereof, webs extending longitudinally of said outer wall and disposed at right angles to said outer wall and in spaced relation between the side edges thereof, said webs being formed integrally with said outer wall, and an inner wall corrugated on vertical lines from side edge to side edge thereof and integrally connected to said webs, said inner wall having a length less than that of said webs.

3. A muffle adapted to be incorporated with the walls of a kiln and cooperate therewith to form a combustion chamber, said muffle comprising spaced inner and outer walls each corrugated on vertical lines, the corrugations on one wall being related to those on the other wall to dispose all portions of said walls in parallel relation, each corrugated wall being provided on its inner side with integral, vertically extending walls disposed at right angles thereto and in alignment with the vertically extending walls on the inner side of the other corrugated wall and arranged to cooperate therewith to reinforce said inner and outer walls.

HARRY M. ROBERTSON. 15
